United States Patent Office

Des. 194,050
Patented Nov. 13, 1962

194,050

PLANTER

Louis Charpentier, Leominster, Mass., assignor to Gilbert Josephson, White Plains, N.Y.

Filed Oct. 20, 1960, Ser. No. 62,551

Term of patent 14 years

(Cl. D35—3)

FIG. I

FIG. 3

FIG. 4

FIG. 2

FIG. 1 is a front perspective view taken from the right side of a planter showing my new design;

FIG. 2 is a left side elevational view thereof;

FIG. 3 is a rear elevational view thereof; and

FIG. 4 is a fragmentary elevational view of one of the legs.

I claim:

The ornamental design for a planter, substantially as shown.
